UNITED STATES PATENT OFFICE.

JESSIE BARTON, OF METHERINGHAM, ENGLAND.

LIFE-PRESERVER.

SPECIFICATION forming part of Letters Patent No. 659,807, dated October 16, 1900.

Application filed March 27, 1900. Serial No. 10,314. (No model.)

To all whom it may concern:

Be it known that I, JESSIE BARTON, a subject of the Queen of Great Britain, residing at Metheringham, Lincoln, in the county of Lincoln, England, have invented certain new and useful Improvements in Life-Preservers, of which the following is a full and complete specification, such as will enable those skilled in the art to which it appertains to make and use the same.

The invention relates to life-preservers; and the object thereof is to provide an improved device of this class whereby persons or goods may be securely housed and protected from wind and wave.

In life-preservers as at present generally constructed the persons or goods buoyed thereby are subject to the buffeting of the elements, and destruction and exhaustion often follow before extraneous assistance is rendered.

The object of the invention is to provide a life-preserved embodying an improved casing in which persons or goods may be securely housed until further assistance is rendered.

The invention consists in the construction and arrangement of parts hereinafter specified.

In the accompanying drawings, forming part of this specification, in which like reference characters denote corresponding parts in the several views, Figure 1 is a perspective view of a life-preserved constructed according to my invention; Fig. 2, a longitudinal section thereof upon the line 2 of Fig. 1, and Fig. 3 a sectional detail of the construction.

In the practice of my invention I provide a life-preserved comprising a tubular base portion A and a relatively-enlarged tubular top portion B. The base portion A consists of a circular base-plate 3 and a top ring 4 of corresponding diameter, said base-plate and top ring being connected by a plurality of spaced body-strips 5, which are circularly arranged, as clearly shown in Fig. 2. The top portion B consists of a base-ring 6 and a top ring 7 of similar diameter, said base-ring and top ring being connected by a plurality of body-strips 8, which are circularly arranged, similar to the body-strips 5 of the base por-

tion A, and an annular member 9 is connected with the top ring 7 by a plurality of radial body-strips 10. The base-ring 6 is connected with the top ring 4 of the base portion A of 55 the life-preserved by a plurality of radially-arranged body-strips 11, arranged in a plane parallel with the plane in which lie the body-strips 10. I also provide a cap or closure 12, which fits the annular member 9 of the top 60 portion of the life-preserved, being provided with a depending annular flange 13, which is passed into the upper end thereof. To enable a person within the life-preserved to firmly secure the closure 12 in position, as shown in 65 the drawings, I provide a catch-arm 14, which is pivoted to the closure 12 at the inner side thereof and is engaged with a screw-eye or hook 15, secured to the annular member 9, as clearly shown in Fig. 2.

The top portion and base portion, respectively, A and B of the life-preserved are covered exteriorly with a skin of canvas or other similar material, (shown at 16,) and this covering is made in any suitable manner impervious to moisture and is of sufficient thickness and stability to resist puncture and similar injuries arising under ordinary circumstances to which the life-preserved may be subjected. The closure 12 is also exteriorly covered with 80 a similar skin 16 and is provided with a pair of chains or other suspension devices 17, which are secured to the top portion B of the life-preserved to prevent misplacement of the closure.

Ranging upwardly from the top of the top portion B of the life-preserved and communicating with the interior thereof is a ventilator-tube 18, provided with a downwardly-deflected perforated head 19, in which is 90 mounted a ball-valve 19^a, which operates to close the tube 18 in the ordinary manner when the water surrounding the life-preserved rises and floats the same, thus preventing entrance of water into the life-preserved. I also provide suitable suspension devices 20, which are connected with the top portion B of the life-preserved and whereby the same may be conveniently suspended upon shipboard or elsewhere.

It is manifest that within the base portion A and top portion B of the life-preserved a

person or persons or goods may be securely housed and effectively protected from the attack of the elements, that said interior will be fully supplied with air through the 5 ventilator-tube 18, and that said ventilator-tube will not admit of the ingress of water, which will be checked by the ball-valve upon rise of the latter.

The annular top portion B of the life-preserve, which is enlarged relative to the base portion A thereof, forms a compartment in which a variety of articles incident to the sustenance of a person may be stored, and various articles may likewise be housed or carried in said top portion.

I do not limit myself to the specific construction and arrangement of parts herein specified, but reserve the right to vary the same within the scope of my invention.

Having fully described my invention, I claim as new and desire to secure by Letters Patent—

1. The herein-described life-preserve, comprising a buoyant tubular body embodying a relatively-large top portion, said body portion consisting of a base-plate, and a plurality of annular members and body-strips rigidly connected together, the entirety being covered by a skin of canvas or other impervious material, and a detachable closure for

said body portion, substantially as shown and described.

2. The herein-described life-preserve, comprising a buoyant tubular body, and means for permitting the ingress of air thereto and for automatically cutting off said ingress, consisting of a tube connected with said tubular body, and provided with a downwardly-directed perforated head in which is mounted a valve, whereby when said valve is floated by the element in which said life-preserve operates said ingress will be cut off, substantially as shown and described.

3. The herein-described life-preserve, comprising a buoyant tubular body embodying a relatively-large top portion, the said body portion consisting of a base-plate, and a plurality of annular members and body-strips rigidly connected together, the entirety being covered by a skin of canvas or other impervious material, substantially as shown and described.

In testimony that I claim the foregoing as my invention I have signed my name, in presence of the subscribing witnesses, this 16th day of March, 1900.

JESSIE BARTON.
